UNITED STATES PATENT OFFICE.

FERNAN OSCAR CONILL, OF CANNES, FRANCE.

MECHANICALLY-DRIVEN MASSAGE APPARATUS.

Application filed May 16, 1928, Serial No. 278,233, and in France October 29, 1927.

The object of the present invention is a mechanically driven massage apparatus and consists in a hollow massage body, carried by a handle, in the interior of said body, a swinging mass eccentrically secured to and rotated by an axle, the latter being journaled in said handle and driven by an electromotor.

An embodiment of the object of the invention is illustrated by way of example on the accompanying drawing.

Figure 1 shows an elevation.

Figure 2 shows a longitudinal section.

Figure 3 shows a cross section along line 15 III—III of Figure 2.

Referring to the figures by characters of reference, the massage apparatus has a driving axle of shaft 1 mounted to rotate within a hollow handle 4. The lower end of said axle is thickened and forms one half 2 of a clutch coupling 3, 17, the other half 17 being fixed to a flexible driving cable 14 driven by an electromotor 16. The two halves 2, 17 of the clutch coupling can be 20 brought into engagement and held in engagement with one another by any suitable known means, such as a screw member adapted to be screwed into the lower end of the handle 4 and to press the clutch half 17 against the clutch half 2. The upper end 25 of the axle 1 has a smaller diameter and carries a swinging mass 8 eccentrically secured thereto by a coin. A screw nut 9 at the end of the axle 1 avoids a sliding or 30 loosening of the swinging mass 8.

The upper part of the handle forms a nave 15, one end screw threaded, the other end bounded by a ring surface 5. On the screw threaded end of the nave 15 a screw 40 nut 6 is fixed, thus the swinging mass 8 lying between both nuts 6 and 9. Between nut 6 and ring surface 5 a pulley 10 loosely embraces said nave 15; the crown of the pulley is screw threaded and carries a cylindrical hood 11, preferably of metal. This hood covers or surrounds the end of the driving axle 1 with its swinging mass, the latter approaching the inner surface of the hood without touching it. The outer surface of 45 the hood 11 is covered by a layer 12 of caoutchouc of the like resilient material, destined to come into contact with the skin to be massaged.

As the pulley 10 can loosely turn round the nave 15 the massage body may be easily 55 rolled along the skin to be massaged without a lifting away of the apparatus from the skin.

The electromotor 16 cut in, the axle 1 will 60 rotate, thus swinging the eccentrically arranged mass 8 around its upper end 7 within the hood 11. Thereby very quick vibrations of the hood are produced, the number 65 of vibrations per minute depending on the speed of rotation of the cable 14 i. e. of the motor 16. These vibrations produce knocking motions on the skin to be massaged, which may be combined with a rolling massage of the body 11, 12.

A massage may be executed as well with 70 the side wall of the body 11, 12 as with its front part; in the latter case a rotating massage is obtained.

What I claim is:

1. In a mechanically driven massage apparatus, the combination of a motor, an axle driven by said motor, a swinging mass eccentrically secured to the end of said axle, a handle surrounding said axle the latter being journaled in the handle, the end of the 80 handle being nave shaped, a pulley loosely mounted on said nave, a hollow hood secured to the crown of said pulley and covering the end of the axle together with the eccentrically mounted swinging mass. 85

2. In a mechanically driven massage apparatus, the combination of an electromotor, a handle, a shaft journaled in the handle, a swinging mass eccentrically secured to one end of said shaft, the other end forming one 90 half of a coupling, the other half of said coupling at the end of a flexible driving cable, the latter driven by said electromotor, the end of the handle forming a nave, a pulley loosely embracing the nave, a hood, secured to the crown of said pulley and surrounding the end of the shaft together with the eccentrically mounted swinging mass, the latter approaching the inner wall of the hood without touching same, the outer surface of the hood covered by a layer of resilient material. 95

In testimony whereof I have signed my name to this specification.

FERNAN OSCAR CONILL.
